[57] CLAIM

The ornamental design for a tire stripping machine or the like, substantially as shown and described.

DESCRIPTION

FIG. 1 is a perspective view of a tire stripping machine or the like showing the new design;

FIG. 2 is a front elevational view thereof;

FIG. 3 is a rear elevational view thereof;

FIG. 4 is a top plan view thereof, the bottom being flat and unornamented;

FIG. 5 is a side elevational view taken from the left of FIG. 1;

FIG. 6 is a side elevational view taken from the right of FIG. 1.

Fig. 1.

Fig. 4.

Fig. 3.

Fig. 2.
